UNITED STATES PATENT OFFICE.

WILLIAM H. SPILLMAN AND FRANK FOWLER, OF ST. JOSEPH, MICHIGAN.

METALLIC THILL.

No. 822,026.

Specification of Letters Patent.

Patented May 29, 1906.

Application filed November 24, 1905. Serial No. 288,824.

To all whom it may concern:

Be it known that we, WILLIAM H. SPILLMAN and FRANK FOWLER, citizens of the United States, residing at St. Joseph, county 5 of Berrien, State of Michigan, have invented a certain new and useful Improvement in Metallic Thills; and we declare the following to be a full, clear, and exact description of the invention, such as will enable others 10 skilled in the art to which it pertains to make and use the same, reference being had to the accompanying drawings, which form a part of this specification.

This invention relates to metallic thills for 15 buggies and wagons, and has for its object a thill bent from sheet metal, whose tubular structure gives it the required tensile and torsional strength, which is even lighter than wood, and which can be produced much 20 more cheaply in view of the increasing scarcity of desirable wood.

In the drawings, Figure 1 is a perspective of the assembled device. Fig. 2 is a perspective from the same point of view of Fig. 1, 25 but with the thill portion and cross-piece or brace withdrawn from engagement with one another. Fig. 3 is a perspective of the under side of the thill and with the struts or braces made integral with the body portion.

30 1 represents the thill, which is bent to nearly circular or tubular form from a single sheet of metal. Around that portion of its body just forward of the curved portion at the rear end are located a pair of sheet-metal members 2, which as regards their encircling portion 2^a serve to bind together the tubular thill, and each of which is provided with ears 3 and 4, which are pierced with several screw-holes and which, in connection with its similar 35 complementary member two or three inches farther toward the curved portion of the thill, form struts or braces adapted for the reception between their parts 3 and 4 of similarly-shaped ears 5 and 6 of the tubular cross-piece 7, which is also bent to form from sheet metal. The shoulder 7^a of this cross-piece is so shaped and bent as to engage with a close fit over the inner side or face of the thill and, in combination with the support 40 afforded by the engagement of the ears 5 and 6 between the ears 3 and 4, reduces to a minimum any tendency to displacement from its normal horizontal position or from its relative position with respect to the thill. The 45

50 holes in the ears 3, 4, 5, and 6 are complementary in their location with respect to one

another, and the two series of ears 3 5 4 and 3 6 4 on each side of the cross-piece 7 are held closely together by bolts C passing therethrough. These two series of ears, together 60 with the engagement against the body portion of the thill of the side portions 7^b of the end 7^a of the cross-piece, form a plurality of differently-disposed bearing-points, which is highly efficient in resisting any buckling 65 tendency of the tubular parts or any tendency of the sheet metal to tear apart. It is of course evident that the other end of the cross-piece 7 is adapted to be attached to the complementary thill in the same manner, and 70 it has been found that this construction is in every way efficient and satisfactory.

Fig. 3 illustrates a slightly-modified form of this construction, in which the place of the 75 slideable clamp and ear members 2 is taken by a construction whereby the ear members are made integral with the body portion of the sheet-metal thill and are simply continuations in the shape desired for the ears of the edges of the sheet-metal blank, which would 80 otherwise be uniformly straight, and as bent over so as to almost touch parallel with one another.

What we claim is—

1. In a tubular thill, in combination with 85 a longitudinal member, a cross-piece having its end fitting closely thereagainst, and having on each side of its end portion ears through which securing-bolts may be passed, and a plurality of brace members encircling said 90 longitudinal member, and each adapted to be attached to one of the ears on said cross-piece, substantially as described.

2. A metallic thill, having in combination 95 a tubular side piece, a plurality of ear members with their body portions engaging about said side piece, and a cross-piece adapted to contact said side piece between said ear members, and having ears projecting from each side of its end portion adapted to register 100 with and be secured to said ear members, substantially as described.

3. A metal thill, having in combination 105 with tubular side pieces, a tubular cross-piece extending from one to the other of said side pieces, and provided at each end with laterally-projecting ears adapted to furnish, in combination with a terminal shoulder on the body portion of the piece, a plurality of bearing-points for engagement against its 110 adjacent side member, and a plurality of attaching struts engaging about each side piece

on each side of the point of contact therewith of the cross-piece, said struts having projecting ears adapted to be attached to the ears on the end of said cross-piece, substantially as described.

4. Metal thills, having in combination side pieces bent to tubular form from blanks of sheet metal, and having projecting from their lateral edges and spaced from one another a plurality of pairs of ears, and a cross-piece, adapted to fit closely with its ends against that portion of each side piece between said ears, and provided with ears projecting from each side of each end adapted to register with and be secured to said first-named ears, substantially as described.

5. A pair of metal thills, having in combination with side pieces bent to form from blanks a cross-piece similarly formed from a

blank and terminating at each end in a shoulder adapted to engage closely against said side pieces at right angles thereto, there being on each side of said shoulder portion laterally - projecting ears adapted to engage against said side pieces, and a plurality of brace members attached to said side pieces one on each side of the point of contact of said brace member therewith and adapted to be attached to said ears on the cross-piece, substantially as described.

In testimony whereof we sign this specification in the presence of two witnesses.

WILLIAM H. SPILLMAN.
FRANK FOWLER.
